UNITED STATES PATENT OFFICE

WALTER E. FIELD, OF PROVIDENCE, RHODE ISLAND

DEVICE FOR DETACHABLY SECURING INTERCHANGEABLE ORNAMENTS TO STRAP ENDS

Application filed June 10, 1932. Serial No. 616,432.

My invention relates to an improved device for detachably securing interchangeable ornaments to strap ends.

While my invention may be employed for any type of strap end, it is particularly adapted for use with identification strap ends normally projecting from various types of bags and to which in some form or other it is desirable to attach an initial of the user or other 5 types of interchangeable ornament. The bags are normally provided with the projecting strap ends and if it is desired to employ initials as the ornament, enough initials may 10 be sold separately for the more common letters of the alphabet with only a small number of bags and the purchaser may select the desired initial and have it readily detachably secured to the strap end by the vendor.

While my invention is primarily adapted 20 for use in attaching any one of a number of different initials to a single bag, it is obvious that if desired, ornaments may be substituted for the initial and the device may be used for other types of strap ends or interchangeability of ornaments if desired.

These and such other objects of my invention as may hereinafter appear will be best understood from a description of the accompanying drawing, which illustrates embodiments thereof.

In the drawing, Fig. 1 is a perspective view of the preferred embodiment of my invention showing a permanent strap end having a detachable ornament or initial secured thereto.

Fig. 2 is a front elevation thereof showing the open position of the pivotable closure caps in dotted lines.

Fig. 3 is a sectional view taken along the line 3—3 of Fig. 2.

Fig. 4 is a disassembled perspective view showing a different type of ornament and illustrating how the detachable ornament member may be secured to the rod means on the end of the strap.

Fig. 5 is a perspective view of the blank I preferably employ to make up the split tubular means attached to the ornament having a closure cap at each end thereof.

Figs. 6-10 illustrate an alternative form of my invention in which the upper end of the

ornament itself is made cylindrical and secured to the strap end by a narrow attaching portion, Fig. 6 being a perspective view of the complete strap end and ornament, Fig. 7 being a front elevation similar to Fig. 2, with the attaching parts shown in section, Fig. 8 being a sectional view taken along the line 8—8 of Fig. 7, Fig. 9 being a disassembled perspective view illustrating the method of attachment and Fig. 10 being a perspective view of the two blanks necessary to make two tubes normally secured to the lower end of the strap end.

In the drawing, wherein like characters of reference indicate like parts throughout, generally indicates a permanent strap end. As stated, my invention is primarily adapted for use in attaching initials or other ornaments to projecting strap ends on bags or other articles of luggage, either dress suit cases, valises, hand bags or otherwise, but the strap end 16 may consist of any well known strap end such as the end of a watch fob etc. to which it is desired to detachably secure any one ornament selected out of a set by the purchaser.

18 illustrates the detachable ornament means of my invention which may consist of the initial shown in Figs. 1-3 or the horseshoe shown in Fig. 4 or any other type of ornament. One of said means has tubular

rod means 20 secured thereto split at the outer end thereof. I employ the word "outer" relative to the line of attachment of said ornaments to the strap ends, said line being outer.

In the embodiment shown in Fig. 4 this tubular means 20 is provided with the transverse split 22 at the upper end thereof and in the embodiment shown in Fig. 9 this tubular rod means 20' is secured to the permanent strap end in a manner to be described, and is provided with a permanent split 22' in the lower end thereof.

In either embodiment said tubular rod means is provided with a pivoted closure cap 24 at each end thereof as shown more particularly in Figs. 2 and 7. The other of said means has the tubular rod means secured to the outer end thereof, thus in the embodiment shown in Fig. 1 the strap end 16 has the rod means 26 secured to the lower end thereof and in the embodiment shown in Fig.

9 the ornament means 18 has the rod means 26' secured to the upper end thereof. In either embodiment the rod means 26 or 26' is 5 slidable within the tubular rod means 20 or 20' and the pivoted closure caps 24 or 24' thereof are bent to a position closing the ends of the tube 20 or 20' to firmly retain the rod means 26 or 26' within said tube 20 or 20'.

The permanent strap end means 16 has its 10 lower end rigidly contained within the edges of a transverse split 28 of a split tubular means 30. In the embodiment shown in Figs. 1-5 said tubular rod means 30 coincides with the rod means 26. In the embodiment shown 15 in Figs. 6-10, however, a separate supplemental tubular rod means 30' is employed soldered to the upper end of the tubular rod means 20'. Thus in the embodiment shown in Figs. 1-5 the rod means 26 is combined with 20 the tubular split rod means 30, whereas in the embodiment shown in Figs. 6-10 the tubular rod means 30' consists of the supplemental tube 30' secured to the upper end of the outwardly split tube 20'.

25 I have illustrated in Fig. 5 the flat blank 19 having the closure caps 24 at each end thereof and from which the tube 20 is bent into the position shown in Fig. 4, the edges 21 of said blank being bent upwardly to 30 form a split 22 in the upper end thereof. I have illustrated in Fig. 10 the two blanks necessary to form the tubes 20' and 30', the blank 21' being supplied with the closure cap 24' at each end thereof and the edges of 35 the side thereof adapted to be bent downwardly to form the transverse split 22' in the lower end thereof and the edges of the flat blank 23 are adapted to be bent upwardly to form the tubular means 30' having the 40 tubular transverse split 28' in the upper end thereof and the tubes are then soldered or otherwise secured together along a line diametrically opposite the splits therein. Thus 45 in the embodiment shown in Figs. 1-5 the blank 21 is bent in the shape shown in Fig. 4 and soldered to the upper end of the ornament 18 and the tube 26 is bent up from the tube 23 shown in Fig. 10 so that the edges of the split may be firmly embedded into the 50 lower end of the strap end 16 as shown in Fig. 4. The tube 20 is then slid laterally over the tubular means 30 and the closure caps 24 bent from the dotted line position 55 shown in Fig. 2 to the full line position shown therein, thus readily detachably securing any desired ornament out of a set to the strap end 16. In the embodiment shown in Figs. 6-10 the interior rod means 26' is 60 attached to the upper end of the ornament, or may be carved out of the shell, metal or other material in the manufacture of the ornament and secured to the ornament 18 by the narrow attaching means 32. In this embodiment the lower end of the strap is secured 65 within the split 28' in the split tube 30' which

in turn is directly soldered to the upper end of the tube 20'. The rod 26' is then inserted within the tube 20' as illustrated in Fig. 9 so that the rod portion thereof will lie in the center thereof and the narrow connecting portion 32 will project downwardly through the split 22' in the lower end of the tube 20'. When the desired ornament has been secured within the tube 20 it is obvious that the caps 24' are pivoted downwards to close up each end of the tube 20'. In the embodiment shown in Figs. 1-5 it is obvious that the strap end 16 itself extends upwardly as shown in Fig. 3 through the split 22 in the upper end of the tube 20.

70 It is thus obvious that I have provided a novel type of device for detachably securing any selected ornament out of a group to a permanent strap end, which is primarily adapted for use with the identifying straps of bags but may be used for any other types of strap ends.

75 It is understood that my invention is not limited to the specific embodiments shown and that various deviations may be made 80 therefrom without departing from the spirit and scope of the appended claims.

85 What I claim is:

1. In a device for detachably securing interchangeable ornaments to strap ends, permanent strap end means, detachable ornament means, one of said means having tubular rod means secured thereto split at the outer end thereof, and having closure caps pivotally mounted on each end thereof, the other of said means having rod means secured to the outer end thereof, slidable within said split rod means and adapted to be permanently retained thereon on pivotal closure of said end closure caps said permanent strap end means having its end rigidly contained within the edges of a transverse split of a split tubular means.

90 2. In a device for detachably securing interchangeable ornaments to strap ends, permanent strap end means, detachable ornament means, one of said means having tubular rod means secured thereto split at the outer end thereof and having closure caps pivotally mounted on each end thereof, the other of said means having rod means secured to the outer end thereof, slidable within 100 said split rod means having its end rigidly contained within the edges of a transverse split of a split tubular means.

105 3. In a device for detachably securing interchangeable ornaments to strap ends, permanent strap end means, detachable ornament means, one of said means having tubular rod means secured thereto split at the outer end thereof, the other of said means having rod means secured to the outer end thereof, slidable within 115 said split rod means having its end rigidly contained within the edges of a transverse split of a split tubular means.

120 4. In a device for detachably securing interchangeable ornaments to strap ends, permanent strap end means, detachable ornament means, one of said means having tubular rod means secured thereto split at the outer end 125 thereof, slidable within said split rod means, said permanent strap end means having its end rigidly contained within the edges of a transverse split of a split tubular means.

130 4. In a device for detachably securing in-

terchangeable ornaments to strap ends, permanent strap end means, detachable ornament means, one of said means having tubular rod means secured thereto split at the outer end thereof, the other of said means having rod means secured to the outer end thereof slidable within said split rod means.

5. In a device for detachably securing interchangeable ornaments to strap ends, permanent strap end means, detachable ornament means, one of said means having tubular rod means secured thereto split at the outer end thereof and having closure means on each end thereof, the other of said means having rod means secured to the outer end thereof, slidable within said split rod means and adapted to be permanently retained therein on pivotal closure of said end closure means.

10. In a device for detachably securing interchangeable ornaments to strap ends, permanent strap end means, tubular means having a transverse split in the upper end thereof having the end of said strap end means secured between the edges of the split thereof, detachable ornament means and tubular means secured to the upper end thereof having a transverse split in the upper end thereof and having closure caps pivotally mounted on each end thereof and adapted to slidably receive said strap end tubular means therein with the strap extending through the split in the upper end thereof.

15. In a device for detachably securing interchangeable ornaments to strap ends, permanent strap end means, tubular means having a transverse split in the upper end thereof having the end of said strap end means secured between the edges of the split thereof, detachable ornament means and tubular means secured to the upper end thereof having a transverse split in the upper end thereof of adapted to slidably receive said strap end tubular means therein with the strap extending through the split in the upper end thereof.

20. In a device for detachably securing interchangeable ornaments to strap ends, permanent strap end means, tubular means having a transverse split portion in the upper end having the end of said strap secured between the edges of the split thereof and a split portion in the lower end thereof and having closure caps pivotally mounted on each end thereof detachable ornament means and rod means secured by a narrow attaching means to said detachable ornament means and slidable within the split tubular means on said strap end means so that said narrow attaching means may rest in the split thereof.

25. In a device for detachably securing interchangeable ornaments to strap ends, permanent strap end means, tubular means having a transverse split portion in the upper end having the end of said strap secured between

the edges of the split thereof and a split portion in the lower end thereof, detachable ornament means and rod means secured by a narrow attaching means to said detachable ornament means and slidable within the split tubular means of said permanent strap end means so that said narrow attaching means may rest in the split thereof.

30. In a device for detachably securing interchangeable ornaments to strap ends, permanent strap end means, tubular means having a transverse split portion in the upper end having the end of said strap secured between the edges of the split thereof and tubular means secured to said tubular means having a split portion in the lower end thereof and having closure caps pivotally mounted on each end thereof, detachable ornament means and rod means secured by a narrow attaching means to said detachable ornament means and slidable within the split tubular means of said permanent strap end means so that said narrow attaching means may rest in the split thereof.

35. In a device for detachably securing interchangeable ornaments to strap ends, permanent strap end means, tubular means having a transverse split portion in the upper end having the end of said strap secured between the edges of the split thereof and tubular means secured to said tubular means having a split portion in the lower end thereof, detachable ornament means and rod means secured by a narrow attaching means to said detachable ornament means and slidable with the split tubular means of said permanent strap end means so that said narrow attaching means may rest in the split thereof.

In testimony whereof I affix my signature.
